UNITED STATES PATENT OFFICE.

GEORGE W. RICHARDSON AND GEORGE H. HIGGINS, OF CHICAGO, ILLINOIS.

VALVE-GEARING FOR INTERNAL-COMBUSTION ENGINES.

1,220,274.

Specification of Letters Patent. Patented Mar. 27, 1917.

Application filed March 15, 1916. Serial No. 84,378.

To all whom it may concern:

Be it known that we, GEORGE W. RICHARDSON and GEORGE H. HIGGINS, both citizens of the United States, residing at Chicago, in the county of Cook and State of Illinois, have invented certain new and useful Improvements in Valve-Gearing for Internal-Combustion Engines, of which the following is a specification.

10 The present invention relates to an arrangement of valve mechanisms, means for actuating the same, and inlet and exhaust passages to the inlet and exhaust manifolds, all of a character suitable for application to 15 gas engines and similar internal combustion motors.

The objects of the invention are, to arrange two inlet valves at a distance of 180 degrees apart and diametrically opposite 20 from a given center; to arrange two exhaust valves 180 degrees apart and diametrically opposite from the same above-mentioned center; to place the exhaust valves a different distance from the above-mentioned 25 given center than the inlet valves, thus creating two circular paths about said center, one of which will embrace the inlet valves and the other the outlet valves; to provide a continuously rotating member for actuating 30 the exhaust and intake valves, which valves, in the construction shown, are applied to a pair of cylinders; to provide two sets of cams on this member, each of which will have a separate circular path of travel during the 35 operation of the device, one path being coincident with the inlet valves and the other path being coincident with the exhaust valves; to configure these cams so as to give a different timing to the exhaust than to the 40 inlet valves; to provide means for operating this rotating member at a proper speed with respect to the speed of the crank shaft; to provide means for eliminating side thrusts from the valves and valve stems; to provide 45 means for inletting and exhausting to inlet and exhaust manifolds arranged on the same side of the engine; to produce a simplicity and compactness of the appliance as a whole; and to provide flat faces on the cams 50 which operate the valves, whereby a full open position of the valves is maintained for a relatively substantial length of time.

And the invention further consists in the features of construction and combination of 55 parts hereinafter described and claimed.

In the drawings:

Figure 1 is a plan view, partly in section, of the mechanisms of the present invention placed in operative relation;

Fig. 2, a section on line 2-2 of Fig. 1, 60 looking in the direction of the arrows;

Fig. 3, a section on line 3-3 of Fig. 1, 65 looking in the direction of the arrows;

Fig. 4, an under face view of a cylinder cap arranged for use with the appliances of 70 the present invention;

Fig. 5, a sectional plan view, showing the ducts leading from the inlet and exhaust valves to the manifolds;

Fig. 6, a detail of the driving means from 75 the crank shaft to the shaft which operates the cam plate; and

Fig. 7, a detail plan of the under side of 80 the cam plate and the driving pinion therefor.

In the art to which the present invention relates, the most common practice of operating the exhaust and intake valves of internal combustion engines is by means of elliptic cams, which strike against tappets, 85 whereby the latter are depressed and the valves operated. The main objection to this type of valve actuating means lies in the fact that the high point of the cam passes very quickly over the tappet, thus causing the valve to close very quickly after the opening and not allowing a proper period of inlet or 90 exhaust.

In the present invention it is intended to 95 eliminate the elliptic cam shaft method of operating the valves and produce this operation by means of a continuously moving member positioned above the tappets, which member will employ cam surfaces arranged in two circular paths of travel for operating 100 the valves, thus materially reducing the operating parts and making a more accurate and smoother operating valve gearing.

The principal feature of the present invention is to operate the valve stems in a 105 manner whereby more gas is admitted to the cylinder and the exhaust gases are enabled to more freely escape during a cycle of operation of the engine. This is all brought about by using cams which have a relatively 110 elongated, flat, high portion which holds the valves, both inlet and exhaust, in full open position for a relatively long period of time. The elliptical cam has its limitations in this respect, because of the fact that the high point thereof is rounded and is of a relatively small area. Thus, with this

elliptical cam, the valves become wide open and immediately proceed to close, giving a relatively short period of full open position, reducing the amount of gas which can enter 5 into the cylinder and reducing the time of exhaust. Holding the valves full open for a relatively long period produces a high efficiency and a consequent economy of gas as compared with the operation of the valves 10 by the well-known elliptical cam.

Referring now to the drawings, the device is shown as applied to a cap-piece 8 adapted to fit upon the top of the engine casing. The cap-piece which is shown is of a type 15 adapted for use with the Northway motor, which has the inlet and exhaust manifolds on the same side of the engine casing. The cap-piece is secured in place by means of suitable bolts passing through bolt holes 9, 20 as is usual, and is provided with water circulating passages 9^a of suitable character.

Extending upward from this cap-piece 8 are suitable standards 10, which are formed with bearings 11 at their upper ends, 25 through which bearings extends a shaft 12. Said shaft is driven, in the construction shown, by means of a sprocket 13, driven by a chain 14, which is driven by a sprocket 14^a, on a shaft 14^b, which latter is driven by a 30 sprocket 15, actuated by a chain 15^a driven by a sprocket 15^b on the crank shaft 16, or a suitable connection therefrom, although the manner of driving the shaft 12 from the crank shaft may be carried out in various 35 ways. A slot 16^a is provided for permitting adjustment of shaft 14^b to take up slack in the sprocket chains.

It will be noticed by referring to Fig. 6 that there is a reduction of approximately 40 two to one in transmitting the speed from the crank shaft to the shaft 12. Secured to the shaft 12 is a spiral pinion 17 which meshes with a spiral gear surface on the periphery of a disk 19 (see Fig. 7). As 45 will be seen, there is a speed reduction of approximately four to one from the pinion 17 to the gear 18, and when the speed reduction of the shaft 12 is taken into consideration, it will be seen that the disk 19 is 50 revolved at approximately an eight to one reduction from the crank shaft.

This disk 19 carries a series of cams 20 and a series of cams 21. The cams 20 are located to the outside of the cams 21, but in 55 alignment therewith; and, as will be seen from the drawings, the cams 20 are somewhat larger in surface than the cams 21, each embodying a relatively broad, flat, high portion. It will also be seen that these two 60 cams are lying in two different circular paths of travel when the disk 19 is rotated. The outer of the cams 20 operate the exhaust valves, and the inner of the cams 21 operate the intake valves. It is a well- 65 known fact that the timing of the exhaust

valves should be different than the timing of the inlet valves, in that the exhaust valves must have a longer period of operation than the inlet valves; and it is not practical to operate by the same cam both the inlet and 70 exhaust valves, hence the provision of two distinct sets of cams for these valves, with the cams for operating the exhaust of a larger area than the cams for operating the inlet valves.

It will be obvious that as the shaft 12 is rotated by the driving connection from the crank shaft, the gear 17 will operate to revolve the disk 19, whereby the cams will be set into motion in paths of travel to operate 80 the respective valves. It is understood that there will be one of the disks 19 used upon each set of cylinders, but detailed description of but one is all that is necessary, the sole difference in the various disks being 85 that each is driven in an opposite direction from the one next adjacent thereto. This will be understood from Fig. 7, wherein it will be seen that the disk to the right is driven in a clockwise direction, and the disk 90 to the left in a reverse clockwise direction. This is brought about by simply reversing the pitch of the pinions 17, and is for the purpose of eliminating side strains from the shaft 12.

The valve arrangements and passages to the inlet and exhaust manifolds are similar for each set of cylinders and detailed description of one arrangement will be sufficient to disclose the construction and operation of all. The valves consist of two inlet valves 22 and two exhaust valves 23. By referring to Figs. 1 and 5, it will be seen that the inlet valves are spaced apart a distance of 180 degrees and are lying equidistant from the axial center of the stub shaft 24, upon which is mounted the plate 19. It will also be seen that the exhaust valves 23 are arranged 180 degrees apart and are lying an equidistance from the axial center of this same shaft 24. Thus, the inlet valves are placed within the same circular path of travel from the center of the shaft 24, and the exhaust valves are placed within the same circular path of travel from 110 this same shaft, the circular path in which the exhaust valves are placed being a greater distance from the center of the shaft than the circular path in which the inlet valves are placed. The paths in which these valves 115 are located are coincident with the path traveled by the cams 20 and 21 on the disk 19, whereby the cams 20 in their rotative movements will strike the tappets to operate the exhaust valves 23, and the cams 21 in 120 their rotative movements will strike the tappets to operate the inlet valves 22.

Each of the valves 22 is provided with a valve stem 25 which extends through a sleeve or bearing 26 and terminates in a head 27, 130

which latter is engaged by a tappet 28 mounted in a sleeve bearing 29 in a frame or support 30; and surrounding the valve stem and tending to keep the valve normally upward and in seated position, is a coil-spring 31. Each of the exhaust valves is provided with a valve stem 32, having a bearing in a sleeve 33; and the stem terminates in a head 34, against which acts a tappet 35, having a bearing in a sleeve 36 in the frame or support 30. A coil-spring 37, suitably held in place, acts to keep the valve normally upward and in seated position. The ends of the tappets 35 and 28 extend above the frame or support 30 and lie in position to be contacted by the cam members as the disk 19 is revolved.

As previously stated, the Northway motor is constructed with the manifold openings for the inlet and exhaust upon the same side of the engine, the exhaust manifold openings being indicated by the numeral 38, and the inlet manifold openings by the numeral 39. By referring now to Fig. 5, it will be seen that there is a passage 40 leading from one of the exhaust valves to one of the exhaust manifold openings 38, and a passage 41 leading from the other exhaust valve to the other exhaust manifold opening 38. The passages 40 and 41 are constructed by configuring the partition to provide outer walls 42, with inner connecting walls 43. By this arrangement, a chamber 44 is provided in the center, with which the inlet valves communicate. These chambers in turn communicate with a chamber 45, through the medium of the openings 39; and this chamber 45 is connected with the inlet manifold 46.

40 The disk 19 is mounted on bearing rings 47, giving it a ball-bearing mounting upon a central post 48, which is held in place by a suitable lock-nut 49; and the lower end of this post is entered into a sleeve 50, which 45 sleeve also carries the support 30. This enables the disk to be easily removed when desired, and also gives to it an anti-friction mounting. A suitable casing 51 may be provided, if desired, for housing the 50 valve gearing mechanism.

It is thought that the operation will be clearly understood from the foregoing, and it is not deemed necessary to describe minutely in what manner the cams 20 and 21 55 act to operate the exhaust and inlet valves respectively as the disk is revolved; and how, by reason of the flat surface on the cams, these valves are maintained fully open for a relatively long period of time. The entire device is compact and strong of nature and fully capable of withstanding the wear and tear of usage. The structure illustrated and described is susceptible of changes and modifications, provided it is maintained 60 within the scope of the appended claims.

We claim:

1. In a valve gearing, the combination of two inlet valves arranged 180 degrees apart and equidistant from a given center, two exhaust valves arranged 180 degrees apart and equidistant from said given center, with the inlet valves a different distance from said center than the exhaust valves, a rotative member, means for rotating said member, a series of cams on said member, said cams 75 lying in two circular paths of travel, the cams in one path acting to operate the inlet valves, and the cams in the other path acting to operate the exhaust valves, the cams for operating the exhaust valves having a 80 larger area of high part than the cams for operating the inlet valves, and each cam for operating the exhaust valves being arranged in radial alignment with a cam for operating the inlet valves, substantially as described.

2. In a valve gearing, the combination of a plurality of cylinders arranged in alignment, an inlet valve on each cylinder, an outlet valve on each cylinder, with the inlet valves of adjacent cylinders arranged 180 degrees apart and equidistant from a point intermediate said cylinders, the exhaust valves on adjacent cylinders being arranged 180 degrees apart and equidistant from said 90 point intermediate said cylinders, with said inlet valves arranged on one circle of travel and the exhaust valves on another circle of travel, and said exhaust valves being out of radial alignment with said inlet valves as respects said point intermediate the cylinders, a member mounted to rotate about a center located at said point intermediate the cylinders, a series of cams on said member, and said cams lying in two circular 95 paths of travel, the cams in one path acting to operate the inlet valves, and the cams in the other path acting to operate the exhaust valves, a shaft arranged above the cylinders and parallel to a line connecting the centers 100 of said cylinders, and a connection between said shaft and rotating member to rotate the latter, substantially as described.

3. In a valve gearing, the combination of a plurality of cylinders arranged in alignment, an inlet valve on each cylinder, an outlet valve on each cylinder, with the inlet valves of adjacent cylinders arranged 180 degrees apart and equidistant from a point intermediate said cylinders, the exhaust valves 115 on adjacent cylinders being arranged 180 degrees apart and equidistant from said point intermediate said cylinders, with said inlet valves arranged on one circle of travel and the exhaust valves on another circle of travel, 120 and said exhaust valves being out of radial alignment with said inlet valves as respects said point intermediate the cylinders, a member mounted to rotate about a center located at said point intermediate the cylinders, 125

- a series of cams on said member, and said cams lying in two circular paths of travel, the cams in one path acting to operate the inlet valves, and the cams in the other path 5 acting to operate the exhaust valves, a shaft arranged above the cylinders and parallel to a line connecting the centers of said cylinders, a connection between said shaft and rotating member to rotate the latter, 10 exhaust manifold openings and inlet manifold openings all arranged on the same side of the engine, passages from the id exhaust valves to the exhaust manifold openings, and means establishing communication between 15 the inlet valves and the inlet manifold openings, substantially as described.
4. In a valve gearing, the combination of a plurality of cylinders arranged in alignment, an inlet valve on each cylinder, an 20 outlet valve on each cylinder, the inlet valves of adjacent cylinders being arranged an equidistance from a point intermediate said cylinders, the outlet valves on adjacent cylinders being also arranged an equidistance 25 from said point intermediate said cylinders, with said inlet valves arranged on one circle of travel and the exhaust valves on another circle of travel and said exhaust valves being out of radial alignment 30 with said inlet valves as respects said point intermediate said cylinders, a member mounted to rotate about a center located at said point intermediate the cylinders, a series of cams on said member, said cams lying in two circular paths of travel, the cams in one path acting to operate the inlet valves, and the cams in the other path 35 acting to operate the exhaust valves, a shaft arranged above the cylinders and parallel to a line connecting the centers thereof, and a connection between said shaft and rotating member to rotate the latter, substantially as 40 described.
5. In a valve gearing, the combination of a plurality of cylinders arranged in alignment, an inlet valve on each cylinder, an outlet valve on each cylinder, the inlet valves of adjacent cylinders being arranged an equidistance from a point intermediate said 45 cylinders, the outlet valves on adjacent cylinders being also arranged an equidistance from said point intermediate said cylinders, with said inlet valves arranged on one circle of travel and the exhaust valves on another circle of travel, and said exhaust valves being out of radial alignment with said inlet valves as respects said 50 point intermediate said cylinders, a member mounted to rotate about a center located at said point intermediate the cylinders, a series of cams on said member, said cams lying in two circular paths of travel, the cams in one path acting to operate the inlet valves, and the cams in the other path 55 acting to operate the exhaust valves, a shaft arranged above the cylinders and parallel to a line connecting the centers thereof, a connection between said shaft and rotating member to rotate the latter, the cams for 60 operating the exhaust valves having a larger area of high part than the cams for operating the exhaust valves, substantially as described.
6. In a valve gearing, the combination of a plurality of cylinders arranged in alignment, an inlet valve on each cylinder, an outlet valve on each cylinder, the inlet valves of adjacent cylinders being arranged an equidistance from a point intermediate said cylinders, the outlet valves on adjacent cylinders being also arranged an equidistance from said point intermediate said cylinders, with said inlet valves arranged on one circle of travel and the exhaust valves on another circle of travel and said exhaust valves being out of radial alignment with said inlet valves as respects said point intermediate said cylinders, a member mounted to rotate about a center located at said point intermediate the cylinders, a series of cams on said member, said cams lying in two circular paths of travel, the cams in one path acting to operate the inlet valves, and the cams in the other path acting to operate the exhaust valves, a shaft arranged above the cylinders and parallel to a line connecting the centers thereof, a connection between said shaft and rotating member to rotate the latter, each cam of the set of cams for operating the exhaust valves being in radial alignment with a cam of the set of cams for operating the inlet valves, substantially as described.
7. In a valve gearing, the combination of a plurality of cylinders arranged in alignment, an inlet valve on each cylinder, an outlet valve on each cylinder, the inlet valves of adjacent cylinders being arranged an equidistance from a point intermediate said cylinders, the outlet valves on adjacent cylinders being also arranged an equidistance from said point intermediate said cylinders, with said inlet valves arranged on one circle of travel and the exhaust valves on another circle of travel, and said exhaust valves being out of radial alignment with said inlet valves as respects said point intermediate said cylinders, a member mounted to rotate about a center located at said point intermediate the cylinders, a series of cams on said member, said cams lying in two circular paths of travel, the cams in one path acting to operate the inlet valves, and the cams in the other path acting to operate the exhaust valves, a shaft arranged above the cylinders and parallel to a line connecting the centers thereof, a connection between said shaft and rotating member to rotate the latter, the cams for operating the exhaust valves having a larger area of high part than the cams for operating the exhaust valves, substantially as described.

ating the inlet valves, and each cam of the set of cams for operating the exhaust valve being in radial alinement with a cam of the set of cams for operating the inlet valves, 5 substantially as described.

8. In a valve gearing, the combination of a plurality of cylinders arranged in alinement, an inlet valve on each cylinder, an outlet valve on each cylinder, the inlet valves of adjacent cylinders being arranged an equidistance from a point intermediate said cylinders, the outlet valves on adjacent cylinders being also arranged an equidistance from said point intermediate said 15 cylinders, with said inlet valves arranged on one circle of travel, the exhaust valves on

another circle of travel, and said exhaust valves being out of radial alinement with said inlet valves as respects said point intermediate said cylinders, a member mounted to rotate about a center located at said point intermediate the cylinders, a series of cams on said member, said cams lying in two circular paths of travel, the cams in one path acting to operate the inlet valves, 20 and the cams in the other path acting to operate the exhaust valves, and means for rotating said member, substantially as described.
